UNITED STATES PATENT OFFICE

ALBERT NAU-TOURON, OF LE VESINET, FRANCE

RING TYPE SPINNING MACHINE

Application filed August 3, 1929, Serial No. 383,317, and in France August 10, 1928.

My invention relates to improvements in the ring type spinning machine described and claimed in my co-pending application Serial No. 248,847, filed January 23, 1928.

5 One of the principal objects of the invention is to do away with the so-called tangent strands travelling from a point on the ring to the winding point on the bobbin and thus eliminate the force to which it is subjected in 55 order to overcome the inertia of the ring during the period of starting of the spindle as well as the force for overcoming the resistance offered by friction to which the ring is subjected during rotation. At the same time 10 15 20 25

My invention allows production of natural or artificial thread of the finest character, flossy and of the least strength under very high spindle speeds, in continuous machines of large production for spinning, twisting and assembling.

My invention will be more readily understood by those skilled in the art in the following description when taken in connection with the accompanying drawings in which—

30 Fig. 1 is a partial sectional view of the first embodiment of my invention;

Fig. 2 is a plan view of Fig. 1 looking from beneath with pulley removed;

35 Fig. 3 is a view similar to Fig. 1 of a second embodiment of my invention;

Fig. 4 is a plan view looking from beneath in Fig. 3 with pulley removed;

Fig. 5 is a view similar to Fig. 1 of a third embodiment of my invention; and

40 Fig. 6 is a section along the line 6—6 of Fig. 5.

Referring to the drawings more in detail and particularly to Figs. 1 and 2, the rotatable ring is indicated by 1 which is supported by means of a ball-bearing 2. Fixed to the ring 2 on the lower edge thereof by means of a screw 2' is a spring 3 of suitable shape and adapted to bear constantly on the spindle 4, thus serving as a flexible driving connection 45 50 55 60 65 70 75 80 85 90 95 100 between the ring 1 and the spindle 4 but

at the same time allowing any desired angular sliding displacement between the elements 1 and 4 if desired under braking action on the ring 1 for which I provide a brake cord 3' of the usual type. In order to increase the 55 adherence of the driving connection I may in certain cases magnetize the spring 3 and I may also employ a plurality of springs 3. In any event I dispose a counter weight 5 on the ring 1 for compensating for the weight of 60 spring 3 which counter-weight is secured by means of a screw 5'. The spindle 4 carries the usual driving pulley 4'.

In the embodiment shown in Figs. 3 and 4, I secure a horseshoe magnet 6 to the lower side of the ring 1. Said magnet 6 preferably carries a flexible arm 7 which is secured in place on the ring by means of a screw 7' and takes the place of the spring 3 in the first embodiment. The poles of magnet 6 straddle the spindle 4 and establish driving connection between the elements 4 and 1 by means of magnetic attraction but at the same time allows a certain angular displacement between the elements 4 and 1 during braking of the ring as 75 in the first embodiment.

I either construct the spindle 4 of a magnetic material or preferably cover the same with a coat of metal which is subject to magnetic attraction.

Likewise I may employ a plurality of magnets 6 instead of one as shown all secured in suitable fashion to the ring 1. As in the first embodiment a counterweight 5 is provided for compensating for the weight of the magnet 6.

In certain cases I may employ one or more electro-magnets having the desired shape and characteristics and I then vary the force of attraction by any suitable means known in the art for altering the driving power.

Referring to Figs. 5 and 6, rigidly secured to the outside of the ring 1 is a collar 8 preferably held in place by means of threads. The lower annular surface of said collar is 95 completely finished and may be flat or other shape and horizontal or of any inclination desired. A sleeve 9 is adapted to rotate about the common symmetrical axis of the device *m-m* with respect to the body 10 rigid with 100

the plate 11 preferably through the medium of a ball bearing 12. Said sleeve 9 has rigidly inserted therein in suitable position a plurality of driving rods 13. Concentrically disposed on each of the rods 13 is a compression spring 14. Said springs function to force annular ring 15 of suitable dimensions against the finished surface of collar 8. Said ring 15 is concentrically disposed with respect to the sleeve 9 and is adapted to be freely displaced in directions parallel to the axis of spindle 4. The said ring 15 is provided with a plurality of holes 13' equal in number to the rods 13 and through which the said rods pass freely.

Because of the free arrangement of ring 15 on collar 9, and the frictional and magnetic engagement of ring 15 with collar 8, it results that the collar 9 drives ring 1 at the same speed of rotation as said collar. The driving connection being frictional and magnetic is not rigid, but yielding and flexible.

Obviously the springs 14 are not limitative and might be replaced by any other analogous expedient such as rings or washers of rubber or other suitable plastic material.

Likewise the driving of ring 15 by sleeve 9 might be accomplished by lugs and notches or their equivalent.

The magnetizing of the ring 15 is optional in which case operation takes place under the same conditions as when non-magnetized with respect to flexibility of action and possibility of collar 8 sliding with respect to ring 15, because of the frictional effect produced by springs 14. Contrariwise I may eliminate the springs 14 and drive solely by magnetic attraction.

40 The sleeve 9 is given a movement of rotation of variable or constant value with respect to that of the spindle 4. For this purpose I preferably employ a driving pulley 16 secured to the sleeve 9 adapted to be driven in turn by a cord or belt driven by any suitable driving element (not shown).

While I have described what I deem to be the preferred forms of my invention I do not wish to be limited thereto as there might obviously be made changes in the materials, forms, dimensions, disposition and the like of the different elements without departing from the spirit of my invention as comprehended within the scope of the appended claims.

Having described my invention what I claim as new and desire to secure by Letters Patent is:

1. In a spinning machine having a spindle, a spinning ring and a plate positioned outside of said spindle and ring, the combination of a collar fixed to said ring, a rotatable sleeve carried by said plate and concentrically positioned with respect to said spindle and spinning ring, an annular collar positioned

on said sleeve and free to slide thereupon, means operatively interconnecting said sleeve to said annular collar adapted to allow relative displacement of said annular collar on said sleeve and resilient means for pressing 70 said annular collar endwise against said first mentioned collar whereby a yielding driving connection is obtained between said sleeve and said feeding ring.

2. In a spinning machine having a spindle, 75 a spinning ring and a plate positioned outside of said spindle and ring, the combination of a collar fixed to said ring, a rotatable sleeve carried by said plate and concentrically positioned with respect to said spindle and spinning ring, an annular collar slidably positioned on said sleeve, a plurality of rods rigidly secured to said sleeve and adapted to slidably engage said annular collar and resilient means for pressing said annular collar against said first mentioned collar whereby 85 a yielding driving connection is obtained between said sleeve and said feeding ring.

3. In a spinning machine having a spindle, a spinning ring and a plate positioned outside of said spindle and ring, the combination of a collar fixed to said ring, a rotatable sleeve carried by said plate and concentrically positioned with respect to said spindle and spinning ring, an annular magnetized collar positioned on said sleeve and free to slide thereupon, and means operatively interconnecting said sleeve to said annular collar and adapted to allow relative displacement of said annular collar on said sleeve whereby a yielding driving connection is obtained between 95 said sleeve and said feeding ring.

4. In a spinning machine having a spindle, a spinning ring and a plate positioned outside of said spindle and ring, the combination of a collar fixed to said ring, a rotatable sleeve carried by said plate and concentrically positioned with respect to said spindle and spinning ring, an annular magnetized collar positioned on said sleeve free to slide thereupon, means operatively interconnecting said sleeve and said annular collar and adapted to allow relative displacement of said annular collar on said sleeve and resilient means for pressing said annular collar against said 100 first mentioned collar whereby yielding driving connection is obtained between said sleeve and said feeding ring.

5. In a spinning machine having a spindle, a spinning ring and a plate positioned outside of said spindle and ring, the combination of a collar fixed to said ring, a rotatable sleeve carried by said plate and concentrically positioned with respect to said spindle and spinning ring, an annular collar slidably positioned on said sleeve, a plurality of rods rigidly secured to said sleeve and slidably engaging said annular collar and a coil spring disposed on each of said rods and adapted to press said annular collar against said first 110

mentioned collar whereby a yielding driving connection is obtained between said sleeve and said feeding ring.

6. In a spinning machine having a spindle, 5 a feed ring member therefor, and a brake device for said feed ring member, the combination of a driving member and power transmitting means interposed between said driving member and said feed ring member, 10 said means comprising a magnetized body, yieldable means connecting said body to one of said members, said magnetized body being disposed in slip engagement with the other member.

15 7. A spinning machine comprising a rotating spindle, a feed ring encircling said spindle, a brake device for said feed ring, and means interposed between said rotating spindle and said feed ring for transmitting 20 the power of rotation of said spindle to said feed ring, an arm fixedly carried by said feed ring and extending toward said spindle, the free end of said arm carrying a magnetized body disposed in slip engagement with said 25 spindle.

In testimony whereof I hereunto affix my signature.

ALBERT NAU-TOURON.
